UNITED STATES PATENT OFFICE.

ISAAC L. EDWARDS, OF AURORA, ILLINOIS.

RAILROAD-TIE PLATE.

Application filed April 5, 1923. Serial No. 630,088.

To all whom it may concern:

Be it known that I, ISAAC L. EDWARDS, residing at Aurora, Illinois, a citizen of the United States, have invented certain new and useful Improvements in Railroad-Tie Plates, of which the following is a specification.

My invention relates to railroad road-bed appliances. My object, stated with reference to what I now consider the best and most complete embodiment of my invention, is to provide a combined tie plate and brace which, with a minimum of metal, will securely hold the rail against the up and down motions that tend to loosen its fastenings, longitudinal motions that cause it to creep and side-wise motions that cause spreading, and which nevertheless will require but a minimum of labor and time for removal of the rail, from, and replacement on, the ties when necessary.

My invention consists in whatever is described by or is included within the terms or scope of the appended claims.

25 In the drawings:

Fig. 1 is a perspective view of a combined tie plate and brace embodying my invention;

Fig. 2 is a transverse section thereof;

30 Fig. 3 is a detail view, in perspective, of the rail brace securing means I prefer to employ; and

Fig. 4 is a detail view in perspective of a different form of rail-clamping key that may be used.

In what I consider now the best embodiment of my invention, I make the tie plate of two metal plates of the same dimensions, and rectangular in form, one laid upon the other, so that, in effect, a laminated plate is the result, thus providing a lower plate 10, and an upper plate 11, upon which the rail base rests, the two plates being provided with alining spike holes 12. The 45 upper plate is preferably made of malleable steel, whereas the lower or base plate may be made of inferior steel or iron, thus enabling a less costly construction than would be the case of a single plate of the same thickness of the two, and made of high grade metal.

On the sides parallel with the rail 13, (shown in broken lines), the base plate has several lugs 14, that lap over the top of the top plate, and thereby any upward tendency of the top plate is resisted.

In the top plate is a transversely extending slot 15, that goes through it from top to bottom, and reaches from its outer edge inward towards the rail, and adjacent each side of said slot, and overhanging the same, is a rib 16, the slot and ribs thus providing a guide, or key-way for a transversely extending key 17, that rests on the top of the base plate and at each side has a flange 18, that lies under one of the overhanging ribs 16, and said key has at its inner end a clamping nose 19, that engages the upper side of the rail flange and thereby the rail is so rigidly clamped that creeping is prevented, and vertical motion of the rail is resisted. Any up motion tendency of the rail under the load of passing trains is transmitted to the top plate, and from the latter to the base plate lugs 14, and thereby by 70 the conjoint action of the lugs 14 and the spikes through holes 12, upward motion of the rail and plate 11 is opposed. Downward pressure of the loaded rail is distributed through the plates of much wider area than that of the rail base immediately above the tie, and, hence, localized, unit pressure, is diminished.

As the top of the rail flange is inclined, and the key 17 moves horizontally, it will 85 be seen that the further the key is driven inward over the flange, the tighter will be its grip.

At its outer end the key 17 has a notch that provides a fork 20, which alines with 90 a notch 21 in the outer edge of the base plate, so that a spike driven into the tie through such notches will anchor the key in rail-flange clamping position, and the sides of the fork or notch engaging the 95 sides of the spike, movement of the key in the direction of the rail length will be prevented.

The base plate is stiffened at its outer edges by a longitudinal rib 22, on each edge, that reaches between the lugs 14, and the top plate lies between the ribs 22.

As shown in Fig. 4, the key 170 and its guide ribs 160, may extend parallel with the rail, and in that case, the rail-engaging nose 190, extends at right angles from the body of the key to overhang the rail flange.

Opposite the guideway of key 17, and alining therewith, is a guide formed of a transversely extending slot 23, and opposite overhanging ribs 24, to receive the base 25,

of a rail brace, 26, that reaches to the side of the rail web, and the under side of the rail head, such a brace being applied to the rail on curves. Thus the same plate 5 may be used on straight track and curves, the braces being applied only where needed. The slot 23 extends through to the top of the base plate, so that the brace base rests on the latter, just as in the case of the 10 key 17. A spike may be used to secure the brace in place, but preferably I employ the key 27, shown best in Fig. 3, which is T-shape, with a central shank 28, that enters a hole 29 in the base plate, after passing 15 through a hole 30 in the brace base, and two vertical lugs 31 that respectively enter sockets 32, formed by surfaces on the two plates, on opposite sides of the brace base.

The rail flange opposite the one engaged 20 by the nose of key 17, is engaged by two lugs 33 on the top plate 11, and integral therewith, so that it will be seen that there is but a single spike to be applied and removed from a tie to secure the rail and 25 permit its removal, and hence, the work and time required for these operations is reduced to a minimum.

It will be seen that by having the lami-

nated plate construction with the top plate removable, any damage to the top plate 30 alone involves no loss or replacement except in the case of the top plate.

I claim:

1. A laminated railroad tie plate, the upper lamina having a guide way for a rail 35 engaging device which guideway includes a slot in such upper lamina that extends transversely inward from the outer edge of the lamina at which the portion of the rail engaging device in the guideway is exposed, 40 and a vertical pin crossing such exposed portion.

2. A laminated railroad tie plate, the upper lamina having a guideway for a rail 45 engaging device formed by a slot in the upper lamina, and ribs at opposite sides of the slot.

3. A railroad tie plate having a transversely extending rail-engaging member, 50 having a base, and a T-shape fastening device that has parts that, respectively, engage surfaces on the base and on the tie plate.

In testimony whereof I hereunto affix my signature.

ISAAC L. EDWARDS.
